United States Patent

Des. 234,390
Patented Feb. 25, 1975

234,390

WORK STATION

Ronald R. Hodges, Grandville, Mich., assignor to
Steelcase Inc., Grand Rapids, Mich.

Filed May 22, 1973, Ser. No. 362,860

Term of patent 14 years

Int. Cl. D6—04

U.S. Cl. D6—167

FIG. 1.

FIG. 2.

FIG. 3.

FIG. 4.

FIG. 5.

FIG. 6.

FIG. 7.

FIG. 1 is a perspective view of a work station embodying the design of my invention;

FIG. 2 is a front elevational view of the work station;

FIG. 3 is an end elevational view of the work station;

FIG. 4 is a rear elevational view of the work station;

FIG. 5 is a top plan view of the work station;

FIG. 6 is a perspective view of the work station with the door shown in an open position; and

FIG. 7 is a perspective view of an alternative embodiment work station embodying the design of my invention.

I claim:

The ornamental design for a work station, substantially as shown.
